JIGGING MACHINE FOR CONCENTRATING
ORES AND OTHER MATERIALS

Stanley Dawson Ware, London, England

Application May 13, 1935, Serial No. 21,233
In Great Britain May 17, 1934

6 Claims. (Cl. 209—425)

The present invention relates to jigging machines for concentrating ores and other materials, particularly of the kind in which a screen submerged in water is given combined vertical and horizontal reciprocating movements from an overhead motion so designed that quick downward strokes of the screen alternate with comparatively slow upward strokes thereof, and quick horizontal strokes towards the feed end of the machine alternate with comparatively slow horizontal strokes towards the discharge end of the machine, the quick horizontal strokes of the screen towards the feed end of the machine synchronizing with the quick falling strokes thereof.

As a result of this motion there is effected a rapid movement of the material over the screen or bed and a quick separation of the values and the waste or gangue with precipitation of the values into compartments from which they are drawn off as required while the tailings pass over the end of the screen.

Probably the most successful jigging machine of the vertical and horizontal reciprocating submerged screen type hitherto in use has been the well known Hancock jigger, the 25 ft. size of which will treat under favourable conditions 600-800 tons of a simple ore in 24 hours. The machine, is, however, large, cumbersome and costly and is actuated by mechanism not well adapted to the essential quick vibration, and is provided with a screen of excessive weight and size producing destructive vibration and giving a capacity greater than required by the usual scale of operations.

Improved designs were attempted by my previous modification of the Hancock, referred to in specification of British Patent No. 166,490 as also by the Franz and Groppe moving screen jiggers referred to in United States specification No. 1,160,502 and English specification No. 253,139 respectively, as well as by exaggerated sizes of plunger jiggers, such as the "May", "New Century", the "Bull", the "Coolie Jig" and others, but with only partial success.

The present invention has amongst its objects to provide a jigging machine of the general character herein referred to of a more favourable cost, size, capacity ratio than former designs.

It further aims so to reduce or minimize the transmission of vibratory forces through the machine that the action of gravity on the ore bed and gangue is permitted to take place with greater freedom from outside disturbing forces.

It further aims inter alia to improve the method of supporting the working parts, to improve

the appliances for preventing the vibrating parts from striking the cams, to reduce the impact shocks of the reciprocating screen, to provide more readily adjustable screen action, a more reliable horizontal motion, to permit higher speed and efficiency, to reduce the weight and cost of the bodywork and mechanism and to permit the head motion and screen to be removed as a unit when desired without derangement of adjustments or bedding.

The invention is illustrated more in a diagrammatic sense by way of example by the accompanying drawings, in which:

Fig. 1 is a side view of the complete machine.

Fig. 2 an end elevation of the same.

Fig. 3 a plan of the same.

Fig. 4 a sectional elevation of the screw adjusters.

Fig. 5 a sectional plan of the same.

Fig. 6 a sectional elevation of a horizontal motion face-cam and cam follower on a sliding carrier.

Fig. 7 a plan of the same with the cam omitted.

Fig. 8 a side view of extensible buffers.

Fig. 9 a plan of the same.

In carrying the present invention into practical effect according to the constructional form shown in the accompanying drawings, the tank body 1 formed of parallel side and converging bottom and end plates is shaped similarly to that in the conventional form of a Harz jigger and supported on V shaped cradle frames or the like 2, but other shapes of the tank body and its supporting means may obviously be adopted within the scope of the present invention.

According to one important feature of the present invention the head motion is not supported by the tank body but on supporting means which transmit a great part or substantially the whole of the vibratory forces (other than those, if any, transmitted to the tank body by the suddenly arrested horizontal movements of the screen) directly to the foundations of the apparatus, whereby not only is the action of gravity on the material permitted to take place with greater freedom from outside disturbing forces, but a tank body construction of reduced weight and cost is made possible. For example a thinner gauge of steel plate may be used for the tank body which may be machine pressed and flanged by existing screw or other presses.

The upper portion of the steel side plates may be reinforced with such material as substantial wood lagging on the interior and the lower por-

tion may be braced on the interior with angle or other section bars or stiffening pieces.

As shown such supporting means take the form of vertical standards or frameworks 200, 200 5 supported directly from the foundations of the apparatus, a concrete bed or floor for example, these standards or frameworks 200, 200 preferably having no rigid or positive connexion with the tank body 1.

10 They may, however if desired, for constructional convenience, form attached or integral parts of the cradle or like supports 2 and serving in such a case as additional vertical tank body to positioning and lateral supporting members to 15 those designated by the reference numeral 2.

15 On such vertical standards or frameworks 200, 200 are mounted girders 3, 3 so as to be supported thereby free from the tank body and on these girders 3, 3 is mounted the head motion for imparting the combined vertical and horizontal reciprocating movements to the screen 11 which is suspended and vertically and horizontally reciprocated as hereinafter described.

The head motion preferred for the purposes of 20 the present invention is one which, as shown, consists of a single shaft 4 mounted in bearings 40 adapted to be driven from any available source of power, for example, through the fast of a pair of fast and loose pulleys 5.

25 On each end of the shaft 4 is mounted to rotate therewith a peripheral jumping cam 16 (Fig. 2).

A feature of the present invention consists in 30 effecting the horizontal reciprocating movements of the screen by a single cam coupled in the preferred form of the means for transmitting the motion of the cam to the screen with a single transmitting unit for that purpose.

Thus to the left of the right bearing 40 (Fig. 1), a single face-jumping cam 6 preferably having 35 alternative tracks 61 and 62 is also mounted on the shaft 4 to rotate therewith, this cam 6 by its rotation imparting the "go" strokes to a roller cam-follower 7 on a reciprocating carrier 8 which is slide guided on guides 9 fixed to the right girder 3 (Figs. 1, 6 and 7), and whose "quick-return" 45 motion is produced by the compression springs 90, 90 interposed between stops on the guides 9 and the corresponding face of the carrier 8.

Injurious contact between the carrier 8 and the 50 cam 6 at the completion of the "quick-return" movements of the carrier is prevented by arranging a yielding stop, e. g., a rubber cushion 22 to receive and lengthen the impact of an appropriately adjustable head 220 mounted in the 55 carrier 8 (Fig. 7).

A further feature of the present invention consists in arranging the "go" stroke of the carrier 8 or an equivalent thereof to be yieldingly transmitted to the suspended screen 11 so that the 60 resistance of such screen to partake of such movement shall be gradually overcome until sufficient energy is stored up for such purpose.

As shown by way of example, the means for so yieldingly transmitting the "go" stroke of the carrier 8 to the screen 11 (towards the discharge end 65 of the machine) takes the form of a laminated spring cross bar 10 with which the carrier 8 makes forked engagement, the spring 10 horizontally bridging the longitudinal sides 12 of the screen 11 and being connected thereto by flexible joints (not 70 shown) so as to accommodate swinging movements of the screen and/or the positioning of the screen so that it may be inclined to the horizontal downwards towards the discharge end of 75 the machine.

The "quick-return" horizontal strokes of the screen 11 are effected, on the passing of the peak point of the cam 6, by stored spring energy, for example, by the energy stored in compression springs 14, the return strokes being stopped by 5 preferably adjustable yielding buffers 15 which may conveniently be of rubber.

The action of the cam 6 and the co-operating spring 10 is so elastically to impart the "go" stroke to the screen 11 that the sum of the resistance of the inertia of the loaded screen and the resistance of the springs 14 is gradually overcome until sufficient energy is stored in the spring 10 to overcome such resistance.

In this way the head motion is largely protected from impact shocks in imparting the desired horizontal reciprocating movements to the suspended screen 11 and conduces to allowing the machine to be run at higher speeds than hitherto.

The forking 80 of the carrier 8 readily permits 20 the screen 11 to be adjusted so that it inclines to the horizontal, if it is desired to be worked in such a position.

For suspending the screen 11 and producing 25 the vertical reciprocating movements thereof, 25 vertically slide guided bridges 17 are mounted crosswise over the cams 16 on slide guides 18 rising from pillars 21, and from the ends of the bridges 17 the screen 11 is suspended by rods 19 having horizontal pivotal connections at their 30 lower ends with the longitudinal side members 12 of the screen 11.

At their upper ends the rods 19 are screw nutted 35 above semi-spherical bearing washers 190 so that the screen is permitted to swing freely.

The rods 19 are extended upwards sufficiently to allow the screen to be adjusted and operated in an inclined as well as in a horizontal position.

Nuts and if desired spring washers 191 are also applied to the rods below the bridges in order to 40 allow the weight of the bridges and the pressure of springs hereinafter referred to, to assist in the essential quick-fall stroke of the screen 11.

As shown more particularly on an enlarged 45 scale by Figs. 4 and 5 each slide portion of each bridge 17 is fitted with a fixed internally screwed sleeve 102 through which is screwed an externally threaded sleeve 103 which has an impact head 104, the position of which, for contacting with a yielding stop, for example, a rubber cushion 105 50 on the top of the pillar 21, may be adjusted to and from the underside of the bridge 17 and when adjusted locked by the nut 108.

The "go" or rising stroke of the bridges 17 is 55 arranged to compress cylindrical compression springs 107 interposed between the locking nut 108 and locking nuts 109 whose adjustment permits the pressure of the springs 107 on the bridges 17 to be regulated.

By adjusting the sleeves 103, not only is adjustment for wear provided, and injurious contact of the bridges with their co-operating cams prevented, but the impact of the falling weight may be so controlled as again to conduce to running the machine at higher than the usual speed. 65

By a further feature of the present invention the usual fixed yielding stops 15 are replaced by adjustable yielding stops permitting the horizontal impacts to be received and absorbed at any desired point towards the termination of the 70 "quick-return" stroke of the screen thereby further conducing to reducing the excessive vibration of previously known machines.

As shown such adjustable yielding stops preferably take the form of linkages 300, 301 and 305 75

tensioned by a screw adjustment 306 whereby a rubber block 304 is gripped against a wedge 307 which can be made to advance or retire behind the block 304 by a screw adjustment 308.

5 In the present apparatus high carbon steel wire screening is preferably used, stretched on a steel frame reinforced with light steel rod bracing to prevent distortion.

In the present apparatus the vertical frames 2 supporting the screen 11 and head motion may be loosened without dismantling, when the screen and the whole of the mechanism can be lifted from the hutch body 1 and removed as one unit without derangement of adjustments or bedding 15 for replacement repairs or renewals.

In the present apparatus light removable wood internal partitions 25 are preferred to be substituted for the usual fixed metal divisions, and an entry space 500 is left at the discharge end. By 20 this means the interior of the tank body 1 and the underside of the screen 11 are rendered accessible for inspection and repairs without removing the screen or deranging adjustments or bedding.

25 By virtue of the design of supporting standards or frames and girders or cross members, a single tank body may be employed with two independently operated screens placed side by side and the resulting plant unit is specially adapted for 30 such purposes as dredge equipment.

Oil-saturated bronze may be substituted for the usual bearing metal, in which case the wearing faces of the reciprocating and rotating parts bushed with this special alloy are rendered independent of lubrication and attention for periods 35 of many months.

The constructional details specified herein as means of effecting improvements may be varied so that this invention applies to screens with 40 trough-shaped extensions for the purpose of discharging the waste above the level of the water, to machines with means of tilting the screen to remove contents, a shallow trough form of tank body and to machines using the usual elevator for 45 discharging waste above the level of the body.

It is understood that screen 11 may be supported by a framework of wood reinforced with metal-work and stays and by crossboards 13 as in existing practice, also that in Figs. 1 and 3 50 the shaft bearings are omitted, also that 23 refers to the usual discharge pipes, and 24 to the levers operating the valves in these pipes.

A trough or other shaped attachment may be fitted to the end of the screen for the purpose of discharging the waste at or about the level of the screen and any means such as water jets may be used in connection with such discharge to assist and expedite the passage of the 55 minerals.

60 What I claim is:—

1. Jigging machine for concentrating ores and other materials of the vertical and horizontal reciprocating submerged screen type having a single driving shaft, vertically and horizontally 65 extending cams fitted on said shaft, transverse members or bridges from which the screen is suspended, and vertical cams co-operating with

said transverse members to impart vertical impulse strokes to said members and the screen a horizontal reciprocating carrier, a horizontal spring bar bridging the screen and flexibly attached to the sides thereof the horizontal impulse strokes being imparted to the screen by the horizontally extending cam through the medium of said horizontally reciprocating carrier engaging said horizontal spring bar. 5

2. Jigging machine for concentrating ores and other materials of the vertical and horizontal reciprocating submerged screen type referred to, comprising in combination a screen, reciprocating bridges from which said screen is suspended, a single driving shaft and peripheral jumping cams on said shaft co-operating with said bridges for causing a vertical reciprocation of said bridges and the screen, said cams and said shaft being situated beneath said bridges, a single facial cam on said shaft for causing a simultaneous horizontal reciprocation of the screen, and a horizontal spring bar bridging the screen and connected thereto, through which bar the horizontal impulse strokes are transmitted to the screen. 20 25

3. A jigging machine as in claim 2, in which there is combined with the facial cam, a cam follower, a reciprocatable holder on which said cam follower is mounted, the spring cross bar with which the carrier makes engagement being connected to the screen by flexible joints. 30

4. A jigging machine as in claim 2, in which there is combined with the facial cam, a cam follower, a reciprocatable holder on which said cam follower is mounted, the spring cross bar 35 with which the carrier makes engagement being connected to the screen and means for adjusting said cam follower.

5. A jigging machine as in claim 2, in which the facial cam, has alternate tracks, and combined therewith is a cam follower, a reciprocatable holder on which said cam follower is mounted, the spring cross bar with which the carrier makes engagement being connected to the screen. 40

6. Jigging machine for concentrating ores and other materials of the vertical and horizontal reciprocating submerged screen type referred to, comprising in combination a screen, transverse bridges from which said screen is suspended, a single driving shaft and peripheral jumping cams on said shaft cooperating with said bridges for causing a vertical reciprocation of said bridges and the screen, said cams and said shaft being situated beneath said bridges, a single facial cam on said shaft for causing a simultaneous horizontal reciprocation of the screen, yielding means in the form of a spring cross bar connected to the screen and through which the horizontal impulse strokes are transmitted to the screen, extensible screen adjusters fitted on 60 said bridges, spring means arranged to be energized by the rising stroke of the screen, and striking cushions arranged to receive and lengthen the impact of the falling screen and bridges and prevent injurious contact of the 65 reciprocating parts with the cams. 50 55 60 65

STANLEY DAWSON WARE.
